UNITED STATES PATENT OFFICE

121,068

DESIGN FOR A CARTON

James Fraterrigo, Tampa, Fla.

Application April 24, 1939, Serial No. 84,715

Term of patent 7 years

To all whom it may concern:

Be it known that I, James Fraterrigo, a citizen of the United States residing in Tampa, in the county of Hillsborough and State of Florida, have invented a new, original, and ornamental Design for Cartons, of which the following is a specification, reference being made to the accompanying drawing, forming a part thereof, in which Figure 1 is a plan view, Fig. 2 a side elevation, and Fig. 3 an end elevation of a carton showing my new design.

I claim:

The ornamental design for a carton, as shown.

JAMES FRATERRIGO.
